UNITED STATES PATENT OFFICE.

WILLIAM P. BETTENDORF, OF DAVENPORT, IOWA.

SWING-MOTION TRUCK.

No. 849,193.

Specification of Letters Patent.

Patented April 2, 1907.

Application filed March 25, 1904. Serial No. 200,000.

To all whom it may concern:

Be it known that I, WILLIAM P. BETTENDORF, a citizen of the United States, and a resident of Davenport, in the county of Scott 5 and State of Iowa, have invented certain new and useful Improvements in Swing-Motion Trucks, of which the following is a full, clear, and exact description.

Heretofore the ends of the bolsters of 10 swing-motion trucks were suspended from the transom at points between the side frames thereof, and the consequence of this construction was to place the weight upon the upper arches of the side frames and create a tendency in the latter to tilt inward.

My invention has for its object the distribution of the weight of the swing-bolster and its load equally upon each side of the side frames and the transferring of the point 15 of suspension of the bolster from the transom to said side frames by novel means that cause the bolster to rise during its sidewise movement in either direction always in a plane parallel to the ball of the rails without disturbing the center of gravity of the car-body and so that the repressive effect of the 20 entire weight of the load will be felt equally throughout the length of the bolster during the displacement thereof from its normal position and automatically restore the same to its 25 position of rest more effectually than is possible where during its side movement the bolster tilts and disturbs the center of gravity of the car-body and feels the repressive effect of the 30 weight of the load mostly on the lowermost end thereof, where it is least needed. This I accomplish by the means hereinafter fully described and as particularly pointed out in the claims.

40 In the drawings, Figure 1 is a plan view of my invention. Fig. 2 is a side elevation thereof. Fig. 3 is a transverse vertical central section of the same. Fig. 4 is a detail view showing the "three-point hanger" in 45 perspective.

Referring to the drawings, A represents the side frames of my improved car-truck, which preferably consists of an upper arch, a lower arch, and two centrally-disposed column-guides, all cast in one piece. Just above the 50 central opening *a* of these side frames the upper arch has projecting laterally therefrom corresponding longitudinally-disposed open bearings *b b* for the upper parallel horizontal 55 portions of journals *c c* of a double link C. This link consists of a continuous loop of bar

metal, which midway its length is bent back over itself, so that the ends (constituting the said journals *c*) are brought near together, and the bends form loops *d d*, in which are seated the ends of the pivot-bar D, from which the platform E, supporting the bolster-springs *e e*, is suspended.

Link C is shown in perspective in Fig. 4 of the drawings, and its proportions and dimensions are such that when one of the journals *c* thereof rests in one bearing *b* of the side frame and the other journal *c* thereof rests in the bearing *b* on the other side of the side frame the vertical plane striking through the axis of pivot-bar D would come midway between the sides of the side frames intermediate said journals. Bar D passes through and has journaled thereon between said loops *d* the bail *f*, projecting centrally and vertically up from the platform E, and the latter is so constructed that it extends equally on both sides of the side frame, and it is provided with seats *g g* for the centers of the elliptical springs *e e*, that are arranged parallel to and at an equal distance from the transverse center of the side frame. These elliptical springs *e* support the ends of the bolster G substantially as shown and are preferred especially for passenger-car trucks. 85 Coil-springs or other forms of springs might be substituted in their place, however. In the drawings bolster G is shown as being made of cast-iron and as having a truss shape between the inside springs, with solid 90 ends extending out through the center opening of the side frames. These ends are provided on either side of the side frames with stop-lugs *h h*, located at such distance apart as to permit the bolster to have a limited longitudinal movement in either direction before such movement is arrested by coming in contact with the outer edges of the open bearings *b b*.

The sills of the central opening *a* of the 100 side frames are preferably flanged laterally and provided with a longitudinal groove therein which forms a seat *j* for the transverse tenon *k*, projecting down from the ends of the spring-plank *k'* and produced by 105 making a transverse depression in the upper surface of said plank, substantially as shown. These transverse depressions thus made form sockets for the shanks of transverse stop-bars I, that project up under the center of the 110 platform E between lugs *e' e'*, depending from the under side of said platform. The

distance between the sides of bars I and said lugs e' when the bolster is in its normal position corresponds to the distance between the stop-lugs projecting from the top 5 of the ends of the bolster and the outer edges of the open bearings b of the side frame and assist in limiting the swing motion of the bolster. Besides the connection supplied by the spring-plank I prefer to connect said side frames at suitable points between the bolster and the journal-boxes by transoms J J. The ends of these transoms are provided with circular trunnions m m, from the ends of which lugs m' project diametrically opposite 15 each other. These trunnions are adapted to be extended through circular openings o in the upper arch of the side frame between the column-guides and the journal-boxes that have diametrically opposite grooves or off-20 sets therein which permit the passage of the pins m' therethrough. When the ends of the transom are inserted in place in these openings in the side frames, the flat sides of the transom are in a vertical plane, when they 25 are properly assembled with relation to said side frames and the said transoms and moved with said trunnions as pivots until their flat sides are in a horizontal position, whereupon pins m are inserted in place and 30 the trunnions cannot be withdrawn. The ends of the transoms are provided with lateral projections K, which extend toward the journal-boxes, and when said transoms are properly secured to the side frame these ex-35 tensions K lie up underneath the inside flange of the upper edge of the side frames. The extremities of these projections K are provided with studs n, that extend up through suitable openings in said flanges and 40 are retained therein by cotters inserted through openings in their ends or in any other suitable manner.

I prefer to use my invention in conjunction with side frames having integral journal-boxes O O at their ends, substantially as 45 shown in Letters Patent of the United States granted to me October 6, 1903, No. 740,617, or any modification of the same. This feature, however, is not essential, al-50 though I prefer their use.

I do not desire to be confined to the exact construction of all of the elements and parts of my invention as hereinbefore set forth, as 55 it is obvious they can be modified and changed without departing from the spirit of my invention, as indicated in the statement contained in the first part of this specification. All such changes, therefore, or modifications I desire to be understood as con-60 templating within the scope of my invention.

What I claim as new is—

1. In a car-truck, the combination with the side frames having bolster-openings therein, of a spring-motion bolster the ends 65 of which extend through said openings, and

devices for sustaining said bolster having three pivot-centers two of which are in connection with said side frames and one with said bolster.

2. In a car-truck, the combination with 70 the side frames having bolster-openings therein, and having bearings on each side of the upper arch of said side frame above said opening, of a swing-motion bolster the ends of which extend through said opening, and links journaled in said bearings and having their pendent portions suspend said bolster at a point in the transverse vertical plane mediate said bearings.

3. In a car-truck, the combination with 80 the side frames having bolster-openings therein, and having bearings on each side of the upper arch of said side frame above said opening, of a swing-motion bolster the ends of which extend through said opening, and 85 an oblong link consisting of an endless bar of metal bent at its center of length back upon itself and having its adjacent ends journaled in said bearings, and its central return-bends sustaining said bolster.

4. In a car-truck, the combination with the side frames having bolster-openings therein, of a swing-motion bolster the ends of which extend through said openings, spring-seats, 95 springs thereon for supporting said bolster, and devices for sustaining said bolster having three pivot-centers two of which are in connection with said side frames and one with said spring-seats.

5. In a car-truck, the combination with 100 the side frames having bolster-openings therein, and having bearings on each side of the upper arch of said side frame above said opening, of a swing-motion bolster the ends of which extend through said opening, 105 spring-seats, springs thereon for supporting said bolster, and an oblong link consisting of an endless bar of metal bent at its center of length back upon itself and having its adjacent ends journaled in said bearings, and its 110 central return-bends sustaining said spring-seats.

6. In a car-truck, the combination with 115 the side frames having bolster-openings therein, and having bearings on each side of the upper arch of said side frame above said opening, of a spring-motion bolster the ends of which extend through said opening, spring- 120 seats extending laterally to each side of said side frames and having an upwardly-projecting bail midway between said lateral extensions, and springs seated on each of said extensions for supporting said bolster, and an oblong link consisting of an endless bar of metal 125 bent at its center of length back upon itself and having its adjacent ends journaled in said bearings, and its central return-bends connected to said bail.

7. In a car-truck, the combination with 130 the side frames having bolster-openings

therein, and having bearings on each side of the upper arch of said side frame above said opening, of a swing-motion bolster the ends of which extend through said opening, spring-seats extending laterally to each side of said side frames and having an upwardly-projecting bail midway between said lateral extensions, and springs seated on each of said extensions for supporting said bolster, and links journaled in said bearings and having their pendent portions pivotally connected to said bail at a point in the transverse vertical plane mediate said bearings.

8. In a car-truck, the combination with the side frames having bolster-openings therein, and transoms connecting the same at points mediate said opening and their ends which have lateral projections at their ends, extending toward the journal-boxes and re-20 movably secured to said frames, of a bolster the ends of which pass through said opening, and means depending from said side frames for suspending said bolster.

9. In a car-truck, the combination with the side frames having bolster-openings therein, and transoms connecting said side frames at points mediate the center of length thereof and the journal-boxes of the same, said transoms having end trunnions that are 30 provided with lateral lugs and are extended through suitable bearings in said side frame, said transoms being also provided with lateral projections extending toward the journal-boxes, and secured to the upper arch of said side frames to prevent the withdrawal of said trunnions, of a bolster the ends of which pass through said bolster-opening, and means depending from said side frames for suspending said bolster.

40 10. In a car-truck, the combination with side frames having bolster-openings therein, of a spring-platform having a bail arising therefrom which is suspended within said bolster-opening, springs supported by said 45 platform on either side of said side frames, a

bolster supported by said springs and means suspending said bail from said side frame.

11. In a car-truck, the combination with side frames having bolster-openings therein, of a spring-platform having a bail arising 50 therefrom which is suspended within said bolster-opening, springs supported by said platform, a bolster supported by said springs and means suspending said bail from said side frame.

55 12. In a car-truck, the combination with side frames having bolster-openings therein, of a suspended spring-platform, devices for sustaining said platform having three pivot-centers the axes of which are all located 60 above said platform, two of which are in connection with said side frames and one with said platform, and a bolster supported by said platform.

13. In a car-truck, the combination with 65 side frames having bolster-openings therein, of a suspended spring-platform, devices for sustaining said platform having three pivot-centers the axes of which are all located 70 above said platform, two of which are in connection with said side frames and one with 75 said platform, springs supported by said platform, and a bolster supported by said springs.

14. In a car-truck, the combination with side frames having bolster-openings therein, 75 of a suspended spring-platform, devices for sustaining said platform having three pivot-centers the axes of which are all located above said platform, two of which are in connection with said side frames and one with 80 said platform, springs supported by said platform on either side of said side frames, and a bolster supported by said springs.

In testimony whereof I have hereunto set my hand this 9th day of March, A. D. 1904. 85

WILLIAM P. BETTENDORF.
